GUARDRAIL ASSEMBLY FOR RAILROAD
TRACK EQUIPMENT

Lee Spencer, Phoenix, Ariz., assignor to American
Brake Shoe Company, New York, N. Y., a cor-
poration of Delaware

Application June 7, 1944, Serial No. 539,074

3 Claims. (Cl. 238—19)

1

The invention relates to railroad track equipment and more particularly to improved guard rail structures. The invention further relates to devices for stiffening or strengthening the guard rail without interfering with clamps, braces or other equipment ordinarily used.

According to a preferred form of the invention, the guard rail structure comprises a guard rail having out-turned ends with spacer blocks engaging the main or running rail. Some of the tie plates underlying the main and guard rails have welded plug stops between the main and guard rails. Certain of the tie plates may have additional welded plug stops on the outer side of the guard rail. Other tie plates may have rail braces welded thereto on the outer sides of the guard rail. The stiffening members may be located between the ties, each member comprising a vertical flange suitably bolted to the web of the guard rail and having a shoulder engaging the lower fillet of the guard rail web. The stiffeners have horizontal foot portions engaging under the base flange of the running rail whereby the weight of trains on the running rail helps prevent the guard rail from tipping.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part hereof, in which:

Fig. 1 is a plan view illustrating the guard rail structure according to the invention;

Fig. 2 is a section on the line 2—2 of Fig. 1 through one of the intermediate tie plates;

Fig. 3 is a section on the line 3—3 of Fig. 1 through the center tie plate;

Fig. 4 is a section on the line 4—4 of Fig. 1 through a stiffening member; and

Fig. 5 is a perspective of one of the individual stiffening members.

In the following description and in the claims, various details will be identified by specific names for convenience, but they are intended to be as generic in their application as the art will permit.

Like reference characters denote like parts in the several figures of the drawings.

In the drawings accompanying and forming

2

part of this specification, certain specific disclosure of the invention is made for purposes of explanation, but it will be understood that the details may be modified in various respects without departure from the broad aspects of the invention.

Referring now to the drawings, the guard rail assembly comprises generally the running rail 10, guard rail 14 and tie plates 11, 12, 13 which rest upon the usual wooden ties 9. Central tie plate 13 and end tie plate 11 are unbraced but intermediate tie plates 12 have rail braces 15. Guard rail stiffeners indicated by 16 are located between the several ties, there being four stiffeners shown in the particular illustration.

The tie plates 11, 12 and 13 are of generally similar construction with certain differences pointed out below. Each tie plate has ribs 21 on the lower side thereof contacting the ties 9. Each tie plate also has an inclined seat 22 for inclining the running rail 10 at a slight angle to the other running rail in accordance with modern railroad practice. The tie plates are also provided with shoulders 23 against which the base flange of the running rail 10 abuts. Tie plates 12 and 13, but not 11, are also provided between the rails, with plug stops 32 set into holes in the tie plate and welded thereto by welding 33 as indicated in Fig. 1.

30 The tie plates also have spike holes 19 which have their outer edges stepped to accommodate different widths of running rail base. Spikes 20 are shown passing through the stepped holes 19 having heads overlying the base flange of the running rail 10.

35 Intermediate tie plates 12 have standard braces 15 welded thereto. Each brace 15 is made up of a vertical portion 26 engaging the fishing surface under the head of the guard rail 14 and over the base flange thereof. The brace 15 has a base 27 and a diagonal 28 connecting the angularly related portions 26 and 27. The brace is connected to the tie plate 12 by welding 29 along both sides and the end of the base 27 as indicated particularly in Fig. 1.

40 The rail braces 28 abut the outside of the guard rail 14 and hold the cut off base flange 30 of the guard rail against plug stops 32. Spike holes for spikes 34 pass through both the base 27 of the rail brace and the tie plate on either side of the diagonal 15. A third hole for a spike 18 passes through the tie plate but not the rail brace.

45 The central tie plate 13 has no rail brace but

the guard rail thrust is taken by a pair of plug stops 40 set in holes in the tie plate on the outer side of the guard rail. Suitable welding 41 connects the plug stops 40 to the tie plates. The tie plates 13 are provided with spike holes through which spikes 36 are driven into the tie beneath.

The end tie plates 11 have plug stops 45 set in holes in the tie plate and connected by welding 46. The plug stops bear against the outer side of the flared ends 60 of the guard rail to take the guard rail thrust. The end tie plates also have holes for spikes corresponding to spikes 36 of tie plate 13.

Referring now also to Figs. 4 and 5, the stiffeners 16 each comprise a web plate 50 having an offset knee 51, a depending leg 53 and a horizontal foot 54. The knee portion 51 provides a shoulder abutting the lower fillet 52 of the web of the guard rail 14. The web plate 50 is provided with spaced holes through which two nut and bolt assemblies 55 pass, these also passing through the web of the guard rail 14. The stiffeners 16 may be conveniently made from flat rolled plate steel stock bent and forged to final shape.

The ends 60 of the guard rail are bent as indicated to form flared easer surfaces and spacing blocks 58 are provided, one at each end. These spacing blocks are so shaped as to fit the fishing contours of both the running rail and the guard rail and are connected to the guard rail 14 by nut and bolt assemblies 59. The spacing blocks 58 have recesses to accommodate the heads of the bolts 59. It will be noted that the spacing blocks 58 are held in abutting position against the running rail but the bolts do not pass through the running rail.

As the wheels of rolling stock roll along the running rail 10, the wheel flanges pass through the flangeway between the running and guard rails. As the wheel flanges engage the guard rail 14, they apply thereto a lateral stress tending to tip it over. This stress is resisted by the rail braces 15 and by the plug stops 40 and 45 at points over the ties. At points between the ties this lateral stress is resisted by the stiffeners 16, the force being applied to the stiffeners through the bolt assemblies 55 and the engagement of the knee 51 with the lower fillet 52, these forces tending to raise the feet 54 of the stiffeners. However, the feet 54 which engage under the base flange of the running rail are held down by the weight of the train on the running rail, thus providing a simple and automatic stiffening action wherein the weight of the train helps resist the lateral thrust of the wheels against the guard rail.

Thus a guard rail construction is provided which is both effective and economical. The stiffeners can be applied to an old guard rail already in place or to a new guard rail. They are easy to install and can be applied to the track without drilling or machining or seriously interfering with the main or running rail. A guard rail assembly made up of the stiffeners, guard rail, braces, plug stops, end spacing blocks, and tie plates may be conveniently assembled in the shop and applied to the running rail as a unit. The stiffeners may be used not only with fabricated or built-up guard rail constructions of the type illustrated in the drawing, but also with other types of guard rail structure. They may be applied to guard rails such as used opposite the frogs of turn-outs and also to long guard railings such as used on sharp railway curves.

These stiffeners relieve and reinforce the braces, clamps or other fixtures ordinarily used, so that if desired, some of these fixtures may be eliminated.

5 The shoulder on the stiffener engaging the lower fillet of the guard rail web relieves the stiffener bolts from strain. If desired, the bolt holes may have sufficient clearance around the bolts to relieve the bolts from shearing stress. In addition, the use of two bolts insures holding the stiffeners in position in case one bolt should fail. The weight of the train on the running rail holds the stiffeners down and thus prevents tipping of the guard rail. This action is accomplished with 10 a minimum of wear on the contacting surfaces of stiffener and running rail since the stiffener does not hold up the weight of the train and thus there is less likelihood of the foot breaking off. The stiffener foot extends well under the running rail to 15 provide increased wearing surface and to take care of inaccuracies in assembly. The stiffeners give support at points between the ties and may be placed not only near the center of the guard rail but near the ends where the gentle curvature 20 of the guard rail carries it away from the running rail. The shoulders 23 act as stops for the running rail and if desired, spike holes may be provided in the tie plates at the inner side of the running rail for spikes to engage over the inner 25 base flange of the running rail to supplement the shoulders 23.

While certain novel features of the invention have been disclosed herein, and are pointed out in the annexed claims, it will be understood that 30 various omissions, substitutions and changes may be made by those skilled in the art without departing from the spirit of the invention.

What is claimed is:

1. In a structure for stiffening a guard rail of standard rolled rail section, said structure comprising a running rail, the said guard rail of standard rolled rail section having a cut-off base flange with its cut-off edge adjacent but spaced from the base flange of the running rail, a plurality of stiffening angles, each stiffening angle comprising a vertical web plate and a flat horizontal foot, said stiffening angles having their web plates disposed against the guard rail web at locations spaced along the length of the guard rail, each said web plate having an opening, said guard rail web having openings in register with the web plate openings of the several stiffening angles, clamping bolts in the respective registered openings, said web plates extending downwardly between said cut-off edge and the edge of the base flange of the running rail, said angle stiffeners having their feet engaging the under surface of said running rail base flange and terminating short of the remote edge of said running rail base flange, all said stiffening angles having the same section regardless of position along the length of the guard rail to permit the same angle to be used at any point regardless of guard rail flare, and a plurality of tie plates under said rails 50 at locations between said stiffening angles, said tie plates having abutments on the side of the guard rail remote from the running rail, whereby the tie plate abutments take the horizontal thrust of the guard rail caused by car wheels, and whereby said stiffening angles are free to stiffen the guard rail web and to prevent tilting or rolling of the guard rail without otherwise interfering with relative movement between said guard rail and running rail.
2. The guard rail structure according to claim

1 in which the web plates each have an offset portion forming a shoulder engaging the lower fillet of the web of the guard rail to relieve shearing stress on said bolts.

3. The guard rail structure according to claim 1 in which rail braces are provided at certain tie plates, said braces engaging the web of the guard rail and secured to their respective tie plates to stiffen the guard rail at locations between said stiffening angles.

LEE SPENCER.
